US00D798546S

(12) **United States Design Patent** (10) **Patent No.:** **US D798,546 S**
(45) **Date of Patent:** **** Oct. 3, 2017**

(54) **BOOT COVER**

(71) Applicant: **Taylor Rose Designs LLC**, Reno, NV
(US)

(72) Inventor: **Heather Sallan**, Reno, NV (US)

(73) Assignee: **Taylor Rose Designs LLC**, Reno, NV
(US)

(**) Term: **15 Years**

(21) Appl. No.: **29/567,131**

(22) Filed: **Jun. 6, 2016**

(51) LOC (10) Cl. **02-04**

(52) U.S. Cl.

USPC **D2/901**; D2/897; D2/910

(58) **Field of Classification Search**

USPC D2/897, 901, 910-913, 946, 970, 971

CPC A41D 17/00; A41D 17/005

See application file for complete search history.

(74) *Attorney, Agent, or Firm* — Holland & Hart LLP

(57) **CLAIM**

The ornamental design for a boot cover, as shown and described.

DESCRIPTION

FIG. 1 is a front perspective view of the boot cover showing my new design;

FIG. 2 is a rear perspective view of the boot cover showing my new design;

FIG. 3 is a left side view of the boot cover shown in FIG. 1; FIG. 4 is a right side view of the boot cover shown in FIG. 1;

FIG. 5 is a rear view of the boot cover shown in FIG. 1; FIG. 6 is a front view of the boot cover shown in FIG. 1; FIG. 7 is a top view of the boot cover shown in FIG. 1; and, FIG. 8 is a bottom view of the boot cover shown in FIG. 1. The broken lines in the drawings represent environment and form no part of the claimed design.

1 Claim, 8 Drawing Sheets
